UNITED STATES PATENT OFFICE.

ALFRED C. ABRAMSON, OF ROCKFORD, ILLINOIS.

PIANO BENCH AND CABINET.

1,227,229.

Specification of Letters Patent. Patented May 22, 1917.

Application filed March 28, 1916. Serial No. 87,207.

To all whom it may concern:

Be it known that I, ALFRED C. ABRAMSON, a citizen of the United States, residing at Rockford, in the county of Winnebago and State of Illinois, have invented certain new and useful Improvements in Piano Benches and Cabinets, of which the following is a specification.

This invention relates to piano benches of the class adapted for use both as an ordinary flat top bench when a piano is hand played and which can be converted into a player-piano bench having an inclined seat disposed at a higher elevation than the horizontal seat, so that one bench serves the purpose of an ordinary piano bench and a player-piano bench.

A standard type of bench now used with the ordinary hand played piano is one in which the stand is constructed to provide an open-top music compartment, and the seat is hinged at one side of the stand so as to provide a lid or cover to the music compartment and a seat for the operator. Benches of this type are known as cabinet piano benches and are generally constructed for duet playing.

The primary object of my invention is to provide a cabinet piano bench that is easily and readily convertible into a player-piano bench and designed so as not to interfere with or alter in any way the construction of an ordinary cabinet piano bench, and to effect this desideratum at a minimum cost of production. In other words, my invention contemplates the addition to a standard type of piano bench of a supplemental seat adapted to be brought into use when the bench is employed with a player-piano in such novel manner that the supplemental seat may rest on the top of the horizontal seat board that serves as a lid to the music compartment of the cabinet and may be swung out of this position and into the music compartment, preferably through the top thereof, after the lid has been raised, so that when the lid is lowered the supplemental seat and its means of mounting and support are entirely concealed within the music compartment.

My invention also contemplates the provision of a supplemental player-piano seat that may be easily and readily attached to any standard duet piano bench having an open-top music compartment, thus enabling piano benches already in use and those of

accepted standard design to be converted into player-piano benches at but a slight additional cost. In this connection, I have designed the player-piano seat attachment so that when not in use it will be concealed within the music compartment of the bench and occupy a position at one end of the compartment, so that the opposite end of the same may be employed for holding sheet music. My improvements permit the player-piano seat to be easily moved from its inoperative position within and at one end of the music compartment to an operative position centrally above the seat board of the bench.

Another object is to provide a cabinet music bench in which a supplemental seat is mounted on a double jointed hinge arranged so as not to interfere with the bench design and to permit the said seat to be positioned on the top of the seat board and swung on the double hinge to a concealed position beneath the seat board and within the music compartment.

Other objects and attendant advantages will be apparent as the invention becomes better understood by reference to the following description when considered in connection with the accompanying drawings, showing several embodiments of my invention, in which—

Figure 1 is a view in perspective of a cabinet piano bench embodying my improvements, the supplemental seat being shown in operative position and the bench being broken away to show the mounting of said seat;

Fig. 2 is a plan view of the bench with the seat board removed and the supplemental seat moved to inoperative position;

Fig. 3 is a cross-sectional view through the bench taken on the line 3—3 of Fig. 2;

Fig. 4 is a view in perspective of a modified form of my improvements showing the supplemental seat positioned within the music compartment;

Fig. 5 is a view in perspective of the bench showing the seat board raised and the supplemental seat swung out of the music compartment; and

Fig. 6 is a cross-sectional view through the bench showing the supplemental seat in operative position.

Referring to the drawings, the piano bench of a conventional cabinet type for duet playing comprises a stand formed by

legs 7 joined by end and side rails 8, 8', 9 and 9', respectively, which define the outer walls of a music compartment designated in general by reference character 11, the bottom of which compartment is defined by the bottom board 12. Braces 13 hold the lower ends of the legs in fixed relation. A seat board 14 hingedly mounted at 15 on the side rail 9 serves as a lid or cover for the music compartment and may be swung to upright position to permit access to said compartment, in which position the lid is held by means of a suitable jointed brace 16. It will be apparent that the bench described is in every way complete and provides an open-top music compartment covered by a hinged seat board. Such a cabinet music bench is of a standard type adapted for use with the ordinary hand played piano.

By providing a supplemental seat adapted to rest on top of the seat board and connected to the bench in a novel manner so that the said seat may be concealed within the music compartment, a player-piano bench is provided, which as will be presently apparent, may be converted, at will, into an ordinary piano bench, and vice versa. As shown in Fig. 1, the supplemental seat designated in general by character 17, having an inclined upper face rests on the top of the seat board 14 and is provided on its lower edges with a felt or other suitable facing, so as not to mar the polish of the seat board. This supplemental seat, of a width suitable for a single person to sit on, may be of suitable construction, preferably of a cushioned structure, so that in connection with the incline of the seat there will be no difficulty for the operator to maintain a proper position thereon. One form of seat I have found very practical and simple to manufacture is shown in Figs. 1 to 3 inclusive, consisting of a seat board 18, the top of which may be padded or tufted and supporting blocks or legs 19 secured to the seat board and shaped to support the same in an inclined position.

My invention contemplates the provision of means pivotally securing the supplemental seat to an element of the bench in such manner as not to interfere with or mar in any way the outward design or appearance of the bench, so that the said seat may be swung from an operative position on top of the seat board to an inoperative position beneath said seat board concealed within the music compartment, preferably at one end thereof. In effecting this object, I have provided a double jointed hinge connecting the supplemental seat to an element of the bench at a point within the enclosure of the cabinet and arranged so as to provide an inner and outer hinge, upon the latter of which the supplemental seat

may swing out of operative position to one side of the seat board and upon the former of which the seat may swing to a position beneath the seat board so as to be concealed thereby within the music compartment or cabinet when the seat board is lowered. To enable the supplemental seat to be positioned within the music compartment at one end thereof. I have so secured the double hinge device to the bench that the seat may be slid lengthwise of the compartment. In the embodiment shown in Figs. 1 to 3 inclusive, the hinge device comprises an inner hinge element in the form of an elongated metal strip 21 turned at one edge around a rod 22 that is secured to the upper portion of the inner side of the side rail 9 by brackets 20 or other suitable means. The hinge element 21 thus being pivotally connected to the rod 22 has secured to each end an upstanding portion 23, to the outer end of which is pivotally connected at 24 a hinge element 25, secured to the narrow end of the adjacent block 19. It will be noted that the portion of the hinge element 21 disposed intermediate the blocks 19 serves merely to establish a pivotal and sliding connection of the hinge device to the rod 22 that will be free from undue friction so that the supplemental seat may be easily slid lengthwise of the music compartment after the seat has been moved from its operative position. By means of the hinge structure described, the supplemental seat 18 may be swung on its pivots 24 away from the seat board to a position substantially in the plane of the seat board, which position is limited by the hinge elements 25 abutting against the upright portions 23 of the hinge element 22. The supplemental seat being thus carried out of the path of the seat board, the same may be swung upwardly to allow the supplemental seat to be swung into the music compartment. With the seat board in upright position, the supplemental seat may be slid lengthwise on the rod 22 to one end of the music compartment and thence swung on the said rod as a pivot into the music compartment as indicated in Figs. 2 and 3. A partition 26 shown in Fig. 2 divides the music compartment so that the sheet music contained in the compartment 27 may not enter the seat-containing compartment 28. The operator while swinging the supplemental seat on the pivots 24 bears slightly inwardly on the seat to hold the hinge elements 23 and 25 in abutting relation, so that this relation will be maintained while the seat is being swung into the music compartment. When the seat board is now swung back to normal position it will be manifest that the supplemental seat is entirely concealed within the cabinet and that the bench has every appearance of an or-

5 ordinary cabinet piano bench, as there is nothing whatever to indicate from outward appearance any auxiliary devices, fastening means or parts, which may in any way be connected with a supplemental seat or any other means for converting the bench into use for player-piano purposes. The bench may be converted into use for this purpose by simply raising the seat board, thence 10 swinging the supplemental seat out of the music compartment and sliding the seat lengthwise on the rod 22 to a position centrally intermediate the ends of the compartment, which position is determined by the 15 end of the hinge element 21 abutting against the central bracket 20 and continuing the swinging movement of the supplemental seat until the element 21 abuts against the top of the side rail 9', lowering the seat board 20 to normal position for locking the said hinge element against movement, and finally 25 swinging the supplemental seat in a reverse direction on the pivots 24 into operative position on the top of the seat board.

25 Referring now to a modified form of invention that I have illustrated in Figs. 4 to 6 inclusive, it will be observed that the bench is of the same general type as that first described with the exception that the 30 music compartment is divided by partitions 29 so as to provide individual compartments 31 at the ends of the bench and a central compartment 32 adapted to receive the supplemental seat. In this instance, the 35 supplemental seat designated generally by 17 is hinged directly to the side rail 9' and swings into the compartment 32, a stop bar 33 being provided to limit the downward pivotal movement of the seat within the 40 said compartment. The double joint hinge here employed is the same as that first described with the slight exception that the hinge element 21 instead of being in one piece is formed of separate sections pivotally 45 connected to stationary hinge elements 34 that are in turn pivotally secured to the inner side of the side rail 9'. Also the operation of swinging the supplemental seat from operative to inoperative 50 positions corresponds with the similar movements of the preferred form of supplemental seat with the exception of adjusting the said seat lengthwise of the music compartment. While in the modified embodiment a greater music-storing capacity 55 is provided, due to the two end music compartments, the dimensions of the bench must be slightly larger than those of the preferred form which are of a standard size 60 now in common use. The double hinge, however, of the modified form, aside from adjustment lengthwise of the compartment, is in every respect equivalent to the mounting of the preferred form of seat.

65 From the foregoing, it will be apparent

that the means I have provided both as an attachment and an addition to a standard type of cabinet music bench, are of few parts and simple in design and construction so that the additional cost of making an 70 ordinary cabinet music bench convertible into a player-piano bench is comparatively small. It should be understood, however, that I do not limit myself to the particular arrangement disclosed, since various modifications may be resorted to without departing from the spirit and scope of the invention as expressed in the appended claims.

I claim:

1. A piano bench comprising a stand constructed to provide an open-top music compartment, a seat board covering said compartment and hinged to the stand, a supplemental seat resting on the top of the seat 85 board, and means pivotally securing the supplemental seat to the stand at the side thereof adjacent to the outer edge of the seat board and constructed so that said supplemental seat may be swung on said means out 90 of the path of the seat board permitting the same to be swung to upright position and the supplemental seat to be swung into the inclosure of the stand beneath the seat board so that the latter may be swung back 95 to normal position.

2. A piano bench comprising a stand constructed to provide an open-top music compartment, a seat board covering said compartment and hinged to the stand, a supplemental seat resting on the top of the seat board, and means pivotally securing the supplemental seat to an element of the bench and constructed so that said supplemental seat may be swung away from the top of the 100 seat board and around the outer edge thereof of allowing the seat board to be swung to an upright position, and the supplemental seat thence swung into the music compartment, whereupon the seat board may be lowered 105 to normal position in which to conceal the supplemental seat within and close said music compartment.

3. The combination with a piano bench having an open-top music compartment covered by a seat board, of a supplemental seat adapted to rest on the top of the seat board, and means pivotally securing the supplemental seat to the bench in such manner that the said supplemental seat may be swung on 115 said pivotal means from said position above the seat board to a position beneath the same and within the music compartment without disturbing the mounting of said seat board.

4. A piano bench having a seat board hingedly mounted on a fixed pivot at one side of the bench, a supplemental seat adapted to rest on the top of said seat board, and means independent of the seat board pivot- 130

ally connecting the supplemental seat to the bench in such manner that the supplemental seat may be moved upon said pivotal connecting means from said position above to 5 one beneath the seat board and within the music compartment.

5. The combination with a piano bench having an open-top compartment covered by a top board hingedly connected at one 10 side to the bench, of a seat adapted to rest on the top of said board, and a device secured to the bench at the side thereof adjacent to the free end of the top board and arranged to extend around the free end of the 15 seat board and being connected to the said seat, said device having a plurality of pivotal joints arranged so that the seat may swing on one pivot away from the top board and on its other pivot to carry the seat beneath the board.

20 6. The combination with a piano bench having a seat board hingedly mounted at one side on a fixed pivot, of a supplemental seat adapted to rest on the top of the seat board, and means connecting the supplemental seat with an element of the bench adjacent to a free edge of the seat board, and means including a pair of pivotal joints arranged so that the supplemental seat may 25 swing on one pivot away from the top of the seat board and on the other pivot to a position beneath the seat board.

30 7. The combination with a piano bench having an open-top music compartment covered by a hinged seat board, of a supplemental seat adapted to rest on the top of the seat board, and means securing the supplemental seat to the bench comprising a hinge secured to a rail of the music compartment adjacent to the outer edge of the seat board and connected at its outer end to the seat, said hinge having a second joint adjacent to the seat so that the seat may swing on the second joint away from the top 40 of the seat board and thence on its inner joint to a position beneath the seat board.

45 8. The combination with a piano bench having an open-top music compartment covered by a hinged seat board, of a supplemental seat adapted to rest on the top of the seat board, and double articulated means independent of the seat board securing the supplemental seat to the bench and arranged so that the seat may swing away 50 from the seat board on one of its joints and thence to a position beneath the seat board on its other joint.

55 9. The combination with a piano bench having an open-top music compartment covered by a hinged seat board, of a supplemental seat adapted to rest on the top of the seat board, and double articulated means securing the supplemental seat to an element 60 of the bench adjacent to a free edge of the seat board, the joints of said means being

vertically spaced apart and arranged so that the supplemental seat may be swung on the upper joint away from the seat board and on the lower joint to a position beneath the seat board.

70 10. The combination with a piano bench having an open-top music compartment covered by a hinged seat board, of a supplemental seat adapted to rest on the top of the seat board, and means pivotally connecting the supplemental seat to the bench, said means having pivotal joints disposed when the seat board is in horizontal position substantially in the planes of the top and bottom of the seat board and arranged so that 75 the supplemental seat may swing on said joints from a position above to one below the seat board.

80 11. A piano bench comprising a stand constructed to provide a rectangular open-top music compartment divided transversely into three compartments, a seat board hinged to the stand and serving as a cover to said music compartment, a supplemental seat adapted to rest on the top of the 85 seat board, and means pivotally securing said supplemental seat to an element of the bench adjacent to an outer edge of the seat board and constructed so that the supplemental seat may be swung to a position beneath the seat board in the central compartment and that the seat board may be swung to a horizontal position in which to conceal the supplemental seat and cover the music compartment.

90 12. The combination with a piano bench having an open-top music compartment covered by a seat board hingedly mounted at one side on a fixed pivot so that it may be swung from a horizontal to an upright position to allow access to the music compartment, of a supplemental seat adapted to rest on the top of the seat board, and means pivotally securing the supplemental seat to an element of the bench and constructed so that 95 the supplemental seat may be swung on said means from said position on top of the seat board to a position beneath the same within the music compartment by passing into the same through the open top thereof.

100 13. The combination with a piano bench having an open-top music compartment and a seat board covering said compartment, of a supplemental seat adapted to rest on the top of the seat board, and pivotal means secured within the inclosure of said compartment and extending around the outer edge of the seat board and attached to the supplemental seat, said means being so constructed that the supplemental seat may be swung 105 thereupon into the music compartment after the seat board has been raised to an upright position.

115 14. The combination with a piano bench having an open-top music compartment and 120

a seat board serving to cover said compartment, of a supplemental seat adapted to rest on the top of the seat board, and means adjustably connecting the supplemental seat 5 to the bench so that said seat may be positioned within the music compartment at one end thereof and moved on said means to a position centrally above the seat board.

15. The combination with a piano bench 10 having an open-top music compartment and a seat board serving to cover said compartment, of a player-piano seat, and means connecting said seat with the bench in such manner that the seat may be moved from 15 beneath the seat board adjacent to one end thereof to a position above and centrally between the ends of the seat board.

16. The combination with a duet piano bench having a music compartment, of a player-piano seat pivotally secured to the 20 bench so as to be movable from a position within the music compartment to one above the seat of the bench and being slidable on its pivotal mounting lengthwise of said compartment.

25 17: The combination with a duet piano bench having a music compartment, of a player-piano seat, and means connecting the said seat with the bench in such a manner that the seat may be moved from a position 30 within the compartment at one end thereof to a position above and centrally between the ends of the duet seat of the bench.

ALFRED C. ABRAMSON.
